PERPETUAL CALENDAR OF THE ROLLER
TYPE

Emil Krug, Mannheim, Germany

Application March 3, 1932, Serial No. 596,484, and
in Germany November 5, 1931

1 Claim. (Cl. 49—114)

This invention relates to an improved and simplified perpetual calendar of the type which is set daily and as required by rotatable parts bearing the ciphers and other particulars for determining the day, month and if desired year or any desired seasonal reminders.

Such adjustable calendars as hitherto known and composed of material such as metal have involved the use of more or less elaborate outer casings or frames with journals for the rotatable setting members and other complications which render them expensive to manufacture, liable to injury and inconvenient to set. The object of the present invention is to simplify the construction of such calendars whilst retaining or improving their reliability, simplicity and efficacy.

The invention consists of a calendar having in combination a plurality of separately and independently rotatable parts arranged co-axially side by side and furnished with various peripheral markings indicating months, days, tens units and the like and a casing containing and retaining these parts and having an axial display slot to reveal the particular markings for a single date and open access for the fingers to the rotatable parts to set the same.

The invention is illustrated by way of example in the accompanying drawing in which:

Figure 1 is a perspective view of one form of roller calendar according to this invention.

Figure 2 shows a second form and

Figure 3 is a section on the line 3—3 of Fig. 2.

The perpetual roller calendar according to this invention may be arranged as of the desk or wall type, but for the sake of illustrating the invention the desk type only has been shown. In the form seen in Fig. 1, the casing *a* is of cylindrical form which may be either a complete cylinder with the necessary openings as herein described or a partial cylinder as shown in the second form herein illustrated. This cylinder or cylindrical casing may be made of a wide variety of materials such as cardboard, wood, metal sheet or celluloid. The casing is at one of its ends closed by a fixed or solid end *b* and has its other end closed by a cover *c* which permits of the placing of the interior parts. Within the casing there are several separate and independently rotatable parts lettered *d, e, f, g, h, i, k, m* arranged side by side and co-axially, the axis being that of the cylindrical casing *a* in which the rotatable parts *d, e, f, g, etc.* may be a good working fit. The rotatable parts are shown as mounted on a spindle *n* which passes from end to end of the casing *a* and finds its support in ring-like members *p*, inset in the end *b*

and the cover *c*. A cardboard, paper or like cover plate gummed or otherwise attached to the ends of the casing closes in the bearings and prevents the spindle *n* from working out of place. The casing *a* is provided with a slit *a'*, which may be sufficiently wide, measured circumferentially

to enable the fingers to have access to the separate discs or rotatable parts, *d, e, f, g, h, i, k, m* to set these parts so that the required particulars for a single date are displayed through the slit *a'*.

The display slit *a'*, may, if desired be made narrow and the rotatable parts *d—m* may be moved by the fingers through slots of suitable length arranged, say on the rear side of the cylindrical casing from that shown in the drawing. The

legends or markings of the various discs or rotatable parts *d—m* are indicated on the drawing, the two end parts being shown as blank. These

may be used for advertising matter, customers telephone numbers or any other data desired. It

will also be understood that the number of rotatable parts may be varied without departing from this invention. The rotatable parts bearing their peripheral markings preferably moved with a small amount of friction so as to prevent in-

advert-displacement after the parts have been set. The casing with the roller calendar parts may be supported on a desk stand *q* which may form a pen stand, ash tray or perform any other useful purpose if desired.

In the form of this invention shown in Figs. 2 and 3 the cylindrical casing is only continued for one half of the diameter, the cylindrical part *r* passing over to the prismatic part *r'*, both these parts being formed conveniently from one piece

of sheet metal. The front stand part is formed by a sloping table *r²* which may act as a note block or the like and then the base is formed by

folding round the end *r³* of the plate, this end

stopping short of the wall *r'*, so as to leave an opening *r⁴* in the base through which the fingers may pass to set the rotatable parts *e, f—g* and *h* which are mounted co-axially and side by side on the spindle *n*. The particulars required to indicate a single date are thus brought as required

opposite the display slot *m* which may be relatively narrow, measured circumferentially.

A feature of importance in this invention is the simple form of one part casing herein employed and the direct setting of the peripherally marked discs through an opening or openings in the casing, thus dispensing with all external handles, knobs or the like with their journals and bearings. The article also may come within a price limit which enables it to be used as an advertising

means, for which purpose the discs *d* and *m* may be employed as well as the outer surface of the casing if so desired.

Having now particularly described and ascertained the nature of my invention and in what manner the same is to be performed, I declare that what I claim is:

A perpetual calendar comprising in combination separate discs bearing on their peripheries the ciphers and like markings for days, tens, units and the like, an essentially prismatic casing having its upper part semi-cylindrically formed and carrying at this part a small slot to reveal the corresponding portion of the periphery of the

rotatable discs, the bottom part of the casing showing a large aperture throughout the whole length of the casing and adapted to introduce the fingers for the rotation of the discs, a spindle fixedly supported within the said casing and carrying rotatably the discs normally held in position by friction on the spindle, the latter and the disc being introduced into the casing by means of the said bottom aperture, a desk like projection conveniently constructed in a single piece with the casing and a calendar unit fixed on the projection.
